UNITED STATES PATENT OFFICE

2,098,773

METHOD OF PRESSING SHOES

William C. Card, Jr., Winthrop, Mass., assignor
to Compo Shoe Machinery Corporation, New
York, N. Y., a corporation of Delaware

Original application March 11, 1931, Serial No.
522,738. Divided and this application June 19,
1935, Serial No. 27,288

3 Claims. (Cl. 12—142)

This invention relates to the manufacture of cemented shoes and more particularly to that step in the manufacture of such shoes which involves affixing the outer sole to the lasted upper by means of an adhesive cement.

A general object of the invention is to provide an improved method of cement affixing an outsole to a lasted upper by means of an inflatable pressure applying pad operating in conjunction with an associated shoe supporting means.

More particularly, objects of the invention are to provide a method of pressing an outer sole to an upper which involves a considerable saving in the amount of time and effort expended by the operator, with consequent advantages and economies in production of the shoes.

Other objects of the invention will in part be obvious and will in part appear hereinafter.

The invention accordingly comprises the several steps and the relation of one or more of such steps with respect to each of the others thereof, which will be exemplified in the method herein-after disclosed, and the scope of the application of which will be indicated in the claims.

For a fuller understanding of the nature and objects of the invention reference should be had to the following detailed description taken in connection with the accompanying drawings, in which:

Fig. 1 is a top plan view of one form of apparatus suited to carry out the invention;

Fig. 2 is a side elevation thereof;

Fig. 3 is a longitudinal section of the same apparatus with the position of a pressed shoe indicated in dotted lines;

Fig. 4 is a section on the line 4—4 of Fig. 3; and

Fig. 5 is a front elevation showing the valve mechanism.

This case is a division of applicant's copending application Serial No. 522,738, filed March 11, 1931 which matured into Letters Patent No. 2,059,847 granted Nov. 3, 1936.

The method of the present invention is adapted to expedite sole pressing operations such as sole affixing, laying or leveling, and may be carried out by means of any suitable apparatus. This method can readily be understood when described in conjunction with the herein illustrated form of apparatus which is especially suited to its performance.

Referring more particularly to the drawings, in the form of apparatus shown there is provided a base member 10 which is generally rectangular in shape and may be conveniently made of light

metal such as aluminum or the like. The base 10 is provided with a cavity 11, the bottom of which is shaped to conform in longitudinal contour substantially to a shoe last, and in which is disposed an inflatable rubber pad 12 which may, if desired, be provided with a casing 13 of leather or the like.

Extending medially across the base portion from front to rear is a bow member 14 adapted to support an instep pad 15 and a bearing member 16. The instep pad 15 may comprise a mushroom shaped rubber pad having its stem 17 carried within a recess 18 in a lug 19 which projects downwardly from the bow member 14.

The bearing member 16 may take the form of a flat plate adapted to bear against the upper heel portion of the last and supported from the bow member 14 by a screw nipple 20. This construction permits the bearing member 16 to engage with lasts of varying lengths and makes it unnecessary accurately to position the lasted shoe beneath the bearing member and the instep pad.

The casing 13 has a bottom portion 22 adapted to lie along and conform to the bottom portion of the cavity 11 and a top portion 23, adapted to bear up against the underside of the shoe. The portions 22 and 23 are joined by a vertical portion 24 of a height substantially level with the sole to permit the top portion 23 to bear up above the level of the sole at its periphery so as to exert pressure against the sole even at its extreme edge. To effect this result, it is desirable that the top portion 23 be materially concaved, even when shoes of small vertical height are being constructed. This makes it possible to utilize the same clamp for shoes of different heights without the necessity of having the parts mechanically adjustable since the form of casing employed makes it possible to obtain the effect of such adjustment by the flexibility of the pad itself. The inflatable pad 12 is of such shape and contour as to conform to the interior of the casing.

This vertical portion 24 preferably supports the top portion 23 which constitutes the bearing surface to engage the underside of the sole at a slightly higher level at the instep portion than at the other portions of the shoe, and the bearing surface 23 is also preferably somewhat wider at its center than at the ends in order that the proper pressure may be assured at all points.

A conduit 28 extending through the bottom of the pad 12 and of the base 10 is held in place by a nut 29 to make an air tight joint. This conduit carries at its outer end a valve 30. Such valve may be of any suitable or known type

adapted to permit inflation and deflation of the pad 12. One desirable form of valve for effecting this is shown for example in my Patent No. 2,009,575, granted July 30, 1935.

5 The elongated shape of the bearing member 16 allows varying sizes of shoes to be treated in a press constructed as above described, since omission of a pin to enter the usual last pin hole in the cone of the last on which the upper is lasted 10 eliminates the necessity of adjusting the instep pad 15 and the heel bearing member 16 along the bow member 14, and construction of the bow member 14 in a rigid or fixed form eliminates the pivoted clamping and ball members heretofore 15 usually used, whereby the time and energy of the operator is saved.

The press herein described is desirably connected to a continuous conveyor by means of lugs 45 so that the press may be carried conveniently 20 to and from a shoe receiving station, and it will be understood that mechanism may be employed, either automatic or manual, for connecting with the valve 38 to deflate the pad in order to remove the shoe and to admit air to the pad when a new 25 shoe has been inserted in place.

With the present form of invention, different heights of shoe may be taken care of without the necessity of adjusting the instep pad or the heel pad because the top surface of the casing is such 30 that even when the enclosed pad is well inflated, it will nevertheless extend upwardly around the shoe at the sides of the sole to maintain the adjustment of the sole firmly in contact with the lasted upper to insure the complete adhesion as 35 the cement dries. With this form of the invention, therefore, it is necessary only to insert the lasted shoe in place, and it will be firmly engaged as soon as air is admitted to the pad.

In operating the described apparatus, the operator 40 loads the lasted upper and the outsole, with adhesive therebetween, between an immovable support and an inflatable pad, and the support is kept immovable throughout successive loading operations, the pad alone being inflated through 45 a sufficient vertical displacement to enable it to press the sole against the lasted upper. The pad is so constructed that it is even able to compensate by inflation alone for substantial variations in employed last sizes.

50 From the above description it will be seen that the present method avoids the time consuming adjustments of the toe and heel post supports which heretofore have always been relatively movable with respect to the pad support. It will 55 be understood that this method can be carried out on any suitable form of apparatus in which the toe and heel supports are capable of being kept fixed with respect to the pad support during successive loading operations and in which the 60 pad is capable of pressing the types of shoes to be worked on against such supporting posts. An

especial advantage in the method is obtained when the vertical expansibility of the pad is made great enough to compensate by inflation alone for variations in employed last sizes, even when these range over a considerable scale. It will also be 5 seen that the method is useful in various sole pressing operations such as affixing, laying and leveling.

Since certain changes may be made in carrying out the above method without departing from the 10 scope of the invention, it is intended that all matter contained in the above description shall be interpreted as illustrative and not in a limiting sense.

It is also to be understood that the following 15 claims are intended to cover all of the generic and specific features of the invention herein described, and all statements of the scope of the invention which as a matter of language might be said to fall therebetween.

Having described my invention, what I claim as new and desire to secure by Letters Patent, is:

1. A method of affixing soles to shoes which comprises, locating an outer sole on a lasted upper with adhesive therebetween, loading the 25 lasted shoe between an immovable support and an inflatable pad, keeping said support immovable throughout successive loading operations, and inflating said pad through a vertical displacement sufficient to enable it to press the sole 30 against the lasted upper and to compensate by inflation alone for substantial variations in employed last sizes.

2. A method of affixing soles to shoes which comprises, locating an outer sole on a lasted 35 upper with adhesive therebetween, providing a fluid pressure pad and a pad support, loading a lasted shoe between said pad and a shoe support, keeping said shoe support immovable with respect to said pad support throughout successive 40 loading operations, and expanding the upper surface of said pad through a vertical displacement sufficient to enable it to press the sole against the lasted upper and to compensate by pad expansion alone for substantial variations in 45 employed last sizes.

3. A method of pressing soles on the bottoms of lasted shoes which comprises, providing a fluid pressure pad and a pad support, loading a shoe between said pad and a shoe support with its 50 sole resting on the pad, keeping said shoe support immovable with respect to said pad support throughout successive loading operations, and expanding the upper surface of said pad through a vertical displacement sufficient to 55 clamp said shoe under pressure between the pad and shoe support and to compensate by pad expansion alone for substantial variations in employed last sizes.

WILLIAM C. CARD, JR. 60
